UNITED STATES PATENT OFFICE.

ROBERT B. BUTLER, OF CHICAGO, ILLINOIS.

WINDOW-FASTENING DEVICE.

1,408,862.

Specification of Letters Patent.

Patented Mar. 7, 1922.

Application filed January 22, 1921. Serial No. 439,062.

To all whom it may concern:

Be it known that I, ROBERT B. BUTLER, a citizen of the United States, and a resident of the city of Chicago, in the county of Cook and State of Illinois, have invented certain new and useful Improvements in a Window-Fastening Device; and I do hereby declare that the following is a full, clear, and exact description of the same, reference being had to the accompanying drawings, and to the numerals of reference marked thereon, which form a part of this specification.

This invention relates more particularly to an improved locking device for windows adapted to permit window sashes to be locked from the interior in open positions of adjustment or in closed position.

It is an object of this invention to provide a locking device for balanced window sashes for the purpose of permitting the sashes to be moved into any open position of adjustment and locked in said position from the inner side of the window against movement from the exterior of the window.

It is also an object of the invention to provide a window with a locking device mounted in the window frame for holding the window sashes locked against movement in open or closed position.

Another object of the invention is to provide a window with a sash locking mechanism adapted to be held in release position by a gravity acting latch to permit free movement of a sash.

A further object of this invention is to provide a window with a locking device adapted for holding a sash locked against movement in an open position of adjustment, said device also having means for holding the locking device in release position to permit movement of the sash from either side of the window if desired.

It is furthermore an object of the invention to equip a window frame with sash locking devices manually operable from only one side of the window frame to permit opening of the sashes, said locking devices being spring controlled to cause automatic locking of the sashes in any one of a plurality of open positions of adjustment or in closed positions when actuating members are released by removing the hand of an operator therefrom.

It is an important object of this invention to provide a window locking device of effec-

tive construction operable from the inner side of a window and adapted to be locked in release position to permit movement of the window sashes from either side of the window, and also adapted to cause locking of said sashes in open or closed position against movement from the outer side of the window.

Other and further important objects of this invention will be apparent from the disclosures in the specification and the accompanying drawings.

The invention (in a preferred form) is shown in the drawings and hereinafter more fully described.

On the drawings:

Figure 1 is an elevation of the inner side of a window equipped with a locking device embodying the principles of this invention.

Figure 2 is an enlarged detail section taken on line 2—2 of Figure 1.

Figure 3 is a vertical section of the window taken on line 3—3 of Figure 2 showing the sash balancing weights and parts of the locking device.

Figure 4 is an enlarged side elevation of the window shown in Figure 1.

Figure 5 is an enlarged fragmentary detail section taken on line 5—5 of Figure 1.

Figure 6 is a front elevation thereof.

Figure 7 is a plan view of a sash corner bracket with guide lug.

Figure 8 is a side view thereof.

Figure 9 is a fragmentary elevation of one of the window frame pulley stiles showing the sash guide grooves.

As shown on the drawings:

A window is provided comprising a window frame embracing an inner casing 1 and an outer casing 2 connected in the usual manner by two vertical pulley stiles 3. The upper ends of the stiles 3 are connected by a head board 4 while the lower ends of said stiles are connected by a sill board 5. The pulley stiles 3 are each provided with a vertical upper sash guide groove or slot 6 and a vertical lower sash guide groove or slot 7.

Slidably mounted in the window frame between strip stops 8, 9 and 10 is a lower sash 11 and an upper sash 12 separated by the parting stop 9. The upper corners of the upper sash 12 are cut away to permit metal angle brackets 13 to seat therein. Screws 110 14 are used to hold the angle brackets secured in place. The vertical arm of each

angle bracket 13 has integrally formed at right angles thereto a locking or guide lug 15 having an aperture 16 therein. The guide lugs 15 are disposed in the plane of the upper sash 5 and project through the pulley stile slots 6 into the locking box 17 and the weight box 18, which are provided between the window casings 1 and 2 and the slotted frame stiles 3. The lower corners of the lower sash 11 have angle brackets 19 rigidly secured thereon by screws or other suitable means. An apertured locking or guide lug 20 is integrally formed at right angles on each of the vertical arms of said angle brackets 19. The guide lugs 20 project through the stile slots 7 into the boxes 17 and 18.

Rigidly secured to the upper ends of the frame stiles 3 and the frame head board 4 are pulley brackets 21 for rotatably supporting lower sash pulleys 22 and upper sash pulleys 23. Attached to the guide lugs 20 of the lower sash 11 are two sash cords 24 which are trained over the lower sash pulleys 22 and are connected to a sash counterpoise weight 25 of sufficient weight to counterbalance the weight of the lower sash 11. Sash cords 26 are attached to the guide lugs 15 of the upper sash 12 and 30 are trained over the pulleys 23. The cords 26 are connected to a sash counterpoise weight 27 adapted to counterbalance the upper sash 12.

The locking device for the upper sash 35 12 comprises a latch or locking bar 28 disposed within the box 17 with the upper end pivotally supported on the pulley stile 3. The latch bar extends downwardly below the middle of the window frame and has a 40 plurality of spaced notches 29 in one margin thereof. The lower end of the latch bar 28 is engaged behind a guide strap 30. Attached to the lower apertured end of the latch bar 28 is one end of a coiled control spring 31 the other end of which is secured to the pulley stile 3 to hold the latch bar 45 in vertical locking position with one of the upper sash lugs 15 engaged in one of the notches 29 to hold the upper sash locked 50 in position. The latch bar 28 is bent near its lower end to provide a yoke 32. Pivotally attached to the yoke 32 is one end of a link 33 the other end of which is pivotally connected to the upper end of the inner arm 55 34 of a fulcrumed latch releasing member which is pivotally mounted on a pin 35 at a bent portion of said releasing member. An outer actuating arm 36 is integrally connected with the arm 34 and normally is 60 adapted to be positioned vertically within an open casing 37 secured within a recess cut in the facing board 38 of the inner window casing 1. The arm 36 is provided with a finger opening 39 and furthermore

has the end thereof bent inwardly to form 65 a stop flange 40.

A similar locking device is provided for the lower window sash 11 and comprises a latch or locking bar 41 having the lower end pivotally mounted on one end of the frame sill board 5 or on the lower portion of the pulley stile 3 within the box 17. The latch bar 41 has a plurality of recesses or notches 42 in one margin thereof. The latch bar extends upwardly a little above 75 the middle portion of the window frame behind a guide strap 43. The upper end of the latch bar 41 is pivotally connected to one end of a link 44. The other end of the link 44 is pivotally connected to the 80 inner arm 45 of a member fulcrumed on the pin 35 of the casing 37. An outer actuating arm 46 is integrally connected with the arm 45 and normally is adapted to be positioned vertically within the casing 37. The 85 arm 46 is provided with a finger opening 47 and with an integral stop flange 48. A coiled control spring 49 has one end thereof attached to the upper end of the latch bar 41 and the other end connected to the pulley 90 stile 3.

Each of the arms 36 and 46 has rigidly secured on the inner face thereof a projection or lug 50 to which is pivotally attached one end of a curved or segment shaped gravity acting dog or latching member 51. A notch 52 is provided in each dog 51. Openings are provided in the back wall of the casing 37 to permit the dogs 51 to slidably project therethrough.

The operation is as follows:

With the window sashes 11 and 12 in their closed positions the latch bars 28 and 41 are held in their vertical locking position by the control springs 31 and 49 respectively. When the upper sash 12 is in closed position one of its lugs 15 is engaged in the uppermost notch 29 of the latch bar 28 to hold the upper sash locked against movement. The lower sash 11 in its closed position has one of the lugs 20 thereof engaged in the lowermost notch 42 of the lower sash latch bar 41 thereby holding said lower sash locked against movement.

The upper and lower window sashes 12 and 11 are unlocked by simply pulling the arms or levers 36 and 46 outwardly into the dotted line position of Figure 5, until the pivoted dogs 51 drop by gravity when the notches 52 thereof reach the base plate of the casing 37. With the outward movement of the arms 36 and 46 the inner arms 34 and 45 of the fulcrumed members are actuated to cause the respective links 33 and 44 to throw the latch bars 28 and 41 out of latching engagement with the sash lugs 15 and 20. The dogs 51 engaging the casing back wall act to hold the latch bars 28 and 41 in unlatched

position, thereby unlocking the window sashes 12 and 11 which may now be slidably moved in the window frame to any desired open position of adjustment.

5 To release the latch bars 28 and 41 the dogs 51 are manually lifted a slight amount sufficient to permit the notched ends thereof to disengage the apertured back wall of the casing 37. When this is done the springs 31 10 and 49 act automatically to return the latch bars 28 and 41 back into their normal latching positions as illustrated in Figure 4. If the window sashes are positioned in open positions of adjustment to permit the lugs 15 15 and 20 thereof to engage in notches in the latch bars 28 and 41 the sashes are held locked against movement in open positions of adjustment. Should the lugs 15 and 20 20 of the sashes be positioned so that the notched latch bars do not lockingly engage said lugs the sashes may be adjusted upwardly or downwardly a slight amount until the sash lugs register with certain of said notches to lock the sashes against further 25 movement.

The sashes may be unlocked by pulling the arms 36 and 46 outwardly thereby causing the latch bars 28 and 41 to swing away from the latching lugs 15 and 20. The 30 window sashes are thus unlocked and may be manually raised or lowered as desired. The window sash weights 25 and 27 act to counterbalance the weight of the lower and upper sashes to facilitate movement of the 35 sashes in the window frame.

Each window sash is provided with a locking device which is adapted to be operated independently of the locking device for the other sash. With the locking devices 40 mounted in position in the window frame box 17 the latch bars 28 and 41 are adapted to be readily moved into and out of locking engagement with the sash lugs 15 and 20 to lock the sashes in closed position or in any 45 desired open position of adjustment. When the sashes are locked in open or closed position it is impossible to move the sashes from the exterior of the window. By pulling out the arms 36 and 46 until the notched dogs 51 50 are permitted to lockingly engage the back plate of the casing 37 the latch bars are held in their release position to permit the window sashes to be adjusted in the window frame from both sides of the window.

55 I am aware that numerous details of construction may be varied through a wide range without departing from the principles of this invention, and I therefore do not purpose limiting the patent granted, otherwise 60 than necessitated by the prior art.

I claim as my invention:

1. The combination with a window frame having slots therein, of a sash slidably mounted in said window frame, lugs on said 65 sash projecting through said slots, a coun-

terweight connected with said lugs, a locking device in said window frame, and means for adjusting said locking device into engagement with one of said lugs to hold the sash locked against movement in any one of 70 a plurality of positions of adjustment in the window frame.

2. The combination with a window frame having slots therein, of sashes adjustably mounted in said window frame, lugs on said sashes projecting through said slots, and locking means in said window frame adapted to be adjusted from the inner side of the window frame into engagement with said lugs to hold the sashes locked against movement from the exterior of the window frame in closed and in open positions of adjustment. 75 80

3. The combination with a window frame, of sashes adjustably mounted therein, locking means in said frame to hold the sashes locked in open and in closed positions against movement from the outer side of the frame, and means accessible only from the inner side of said frame adapted to be operated to 85 cause release of said locking means to permit adjustment of the sashes from both sides of the window. 90

4. The combination with a window frame, sashes adjustably mounted therein, lugs on 95 said sashes projecting into said frame, latching members in said frame adapted to engage said lugs to hold the sashes locked in closed and in open positions of adjustment, means connected with said latching members 100 for moving the same out of locking engagement with said lugs to permit movement of said sashes, and gravity dogs on said means adapted to engage the frame to hold said latching members locked in release position. 105

5. The combination with a window frame having slots therein, counterbalanced sashes adjustably mounted in said frame, lugs on 110 said sashes projecting through said slots into said frame, notched latch bars pivotally mounted in said frame, resilient means connected with said latch bars and with said frame for holding the latch bars in engagement with said lugs to hold the sashes locked in closed or in open positions of adjustment, 115 an apertured casing recessed into the inner side of said frame, actuating members fulcrumed in said casing and projecting into said frame, links connecting said fulcrumed members with said latch bars, said fulcrumed members adapted to be operated to cause movement of said latch bars into release position out of engagement with said lugs against the action of said resilient means to permit movement of the sashes in 120 said frame, and notched gravity acting members pivoted on said fulcrumed members and projecting through said casing into said frame, said gravity acting members adapted to engage said casing to hold the latch bars 125 130

locked in release position against the action of said resilient means to permit adjustment of the sashes in the window frame.

6. The combination with a slotted window frame, of a sash adjustably mounted therein, a lug on said sash projecting into the frame through the slot thereof, and means in said frame operable only from the inner side of the frame for engaging said lug to hold the sash locked in said frame in closed or in open positions against movement from the outer side of the frame.

7. The combination with a window frame and a sash thereof, means on said sash projecting into said frame, a notched latch bar adjustably mounted in said casing, means for holding said latch bar in release position to permit adjustment of the sash in the window frame, and a spring connected with said latch bar adapted to automatically move the same into locking engagement with the means on said sash to hold the sash locked in a predetermined open position of adjustment when said second mentioned means is released.

8. In a window fastening device, a bar extending along the window casing beside the window sash, said bar having notches therein, a lug on the sash adapted to co-operate with said notches to secure the sash in position, a spring biasing said bar toward lug engaging position, said bar being pivoted to the window frame near one end of the sash and means in the window frame near the other end of said sash for moving said bar against the influence of said spring.

9. In a window fastening device, means for locking the upper sash against movement, means for locking the lower sash against movement, two releasing means, one for moving each of said locking means to unlock position, and a common pivot on which said two releasing means are mounted.

In testimony whereof I have hereunto subscribed my name in the presence of two subscribing witnesses.

ROBERT B. BUTLER.
